UNITED STATES PATENT OFFICE.

JEROME RICE, OF NEW YORK, N. Y., ASSIGNOR TO WIMELBACHER & RICE, OF NEW YORK, N. Y., A FIRM.

DESIGN FOR A GLOVE GAUNTLET.

Application filed May 9, 1922. Serial No. 2,144. Term of patent 3½ years.

To all whom it may concern:

Be it known that I, JEROME RICE, a citizen of the United States, and a resident of the city of New York, borough of Manhattan, in the county and State of New York, have invented a new, original, and ornamental Design for a Glove Gauntlet, of which the following is a specification, reference being had to the accompanying drawing, forming a part thereof, wherein the gauntlet is distinguished by means of a vine effect showing conventionalized berries and leaves in color

contrasting with the ground color of the gauntlet.

The drawing shows the back or obverse portion of a pair of gloves, said gloves being placed edge to edge to illustrate the full repeat of the design.

What I claim and desire to secure by Letters Patent is:—

The ornamental design for a glove gauntlet, substantially as shown and described.

JEROME RICE.
